(57) **CLAIM**

The ornamental design for a child safety seat as shown and described.

DESCRIPTION

1. Child safety seat

1.1 is a perspective view of a child safety seat showing the new design;

1.2 is a front elevational view thereof;

1.3 is a rear elevational view thereof;

1.4 is a first side elevation view thereof;

1.5 is a second side elevational view thereof;

1.6 is a top plan view thereof;

1.7 is a bottom plan view thereof; and

1.8 is an enlarged area of the child safety seat shown in drawing figure 1.7.

The broken line showing a portion of the child safety seat is included for the purpose of illustrating environmental structure and forms no part of the claimed design.
